UNITED STATES PATENT OFFICE.

EDWARD J. GOLDEN, OF CHICAGO, ILLINOIS, ASSIGNOR TO CHICAGO SCAFFOLD COMPANY, OF CHICAGO, ILLINOIS, A CORPORATION OF ILLINOIS.

SCAFFOLD.

1,187,060.

Specification of Letters Patent. Patented June 13, 1916.

Application filed December 16, 1915. Serial No. 67,199.

To all whom it may concern:

Be it known that I, EDWARD J. GOLDEN, a citizen of the United States, residing at Chicago, in the county of Cook and State 5 of Illinois, have invented new and useful Improvements in Scaffolds, of which the following is a specification.

My invention relates to improvements in scaffolds of the type involving a series of 10 cross-pieces upon which the planking of the scaffold is laid, and hoisting frames connected with the ends of the cross-pieces and carrying drums on which cables depending from outriggers extending from the building, in connection with which the scaffold 15 is to be used, are wound, means being provided on the frames whereby the cables may be wound upon or unwound from the drums to raise or lower the scaffold, as desired. The 20 cross-pieces supporting the planking may be provided in a single pair, where a relatively short scaffold only is desired, or in any other desired number, the various hoisting cables serving to support the scaffold at the 25 desired elevation; and my invention also relates to hoisting frames in general.

Certain of my objects are to provide improvements in the means securing the hoisting frames to the cross-pieces, to the end 30 that the structure will be rendered safe, relatively light in weight and economical of construction; to provide novel, simple and economical means for supporting an overhead covering for the scaffold; and to 35 provide improvements in hoisting frames.

Referring to the accompanying drawings, Figure 1 is a perspective detail view of a scaffold constructed in accordance with my invention. Fig. 2 is a view in elevation of 40 the lower end of one of the hoisting frames. Fig. 3 is a section taken at the line 3 of Fig. 2 and viewed in the direction of the arrow. Fig. 4 is a view in side elevation of one of the similar hoisting frames employed, together 45 with the operative parts carried thereby. Fig. 5 is a view of the structure shown in Fig. 4 but viewed at a right-angle thereto, and Fig. 6 is a plan view of one of the two similarly shaped ends of each cross-piece.

In the drawings, I have shown a scaffold made up from but two cross-pieces, for clearness of illustration, though, as hereinafter explained, as many of the cross-

pieces as desired may be used, the cross-pieces being illustrated at 7, and preferably formed of metal having horizontally extending flanges 8 along their upper edges, the particular cross-pieces shown being of L-shape in cross-section. Each cross-piece 7 carries two hoisting or drum supporting frames represented at 9, Fig. 1, these frames being secured to the crossbars at the ends of the latter, by constructing them as follows:

Each of the frames 9 is formed of two 65 side-members 10, which are shown as, but need not necessarily be, separate members secured together in spaced relation by cross-bars 11 carrying spacers 12. The ends of the cross-bars 11 are threaded to receive 70 nuts 11^a for clamping together the parts of the hoisting frame, the nuts on the uppermost bars terminating in eyes 11^b which latter serve to receive and hold a guard-cable (not shown) for the platform of the 75 scaffold. The lower ends of the side-members 10, which preferably are turned back upon themselves to form eyes 13, are slotted, as indicated at 14, at which slotted portions 80 these frames straddle the vertical web of the cross-piece 7, and are rigidly secured in place thereon as illustrated, by bolts 15, which pass through the eyes 13, and registering perforations in the said webs, the horizontal flanges 8 of the cross-pieces 7 85 being cut away, as indicated at 16 and 16^a, to permit of the assembling of the hoisting frames with the cross-pieces, as stated.

Any suitable cable-operating means may be provided on the frames 9 for engaging 90 and operating cables 17 which support the scaffold, and, as stated above, in practice are suspended from outriggers positioned on the building above the scaffold. The cable-operating means illustrated, form the 95 subject of an application for United States patent copending herewith, and a brief description thereof will, therefore, suffice. In each of the frames 9 a shaft 18 is journaled, each shaft carrying a drum 19 about which the lower end of the cable 17, with which it co-operates, is wound, the cable 17 passing over a pulley 20 journaled on the uppermost spacer 12. Rotatable upon and shiftable longitudinally of the shaft 18 is a lever 100 21, between which and the adjacent side 10, a coil-spring 22 is interposed. The lever 21 co-operates with a circular series of teeth

23 projecting laterally from one end of the drum 19. Each tooth 23 is constructed with a shouldered portion 24 and a sloping portion 25. The arrangement is such that the 5 lever 21 may be raised without actuating the drum 19, the lever riding over the surfaces 25, in which movement the spring 22 yields. The lever 21, however, interlocks with the shoulder 24 of one of the teeth when the 10 lever is depressed, and this causes the drum 19 to be rotated in an anti-clockwise direction, in Fig. 4, to wind the cable upon the drum, and thus elevate the scaffold. The pawl 26, rigid on a sleeve 27, journaled on 15 the spacer 12 immediately above the shaft 18, co-operates with ratchet-teeth 29 on the drum 19, and prevents the drum from rotating in the direction opposite to that in which it is rotated when actuated by the lever 21. 20 When, however, it is desired to lower the scaffold by unwinding the cables, the pawl 26 may be readily swung out of the path of movement of the teeth 29 while the drum 25 is rotating in a clockwise direction, under a resistance presented by the operator bearing down on the lever 21 sufficiently to permit the cable to pay out at the desired speed, the pawl 26 being swung manually into engagement with one of the teeth 29 each time 30 the lever 21 completes an upward movement.

The planking represented at 30 and which would extend substantially parallel with the side of the building adjacent to 35 which the scaffold would be hung, extends from, and is supported by the cross-pieces 7, as represented in Fig. 1. It is preferred that some means be provided for preventing the planking from shifting cross-wise of the 40 cross-pieces 7. Any desirable means may be employed, those shown, however, being preferred, and comprising plates 31 having notches 32 in one edge. These plates are nailed, as indicated at 33, to the upper 45 surface of the planking adjacent the outer side of each frame 9, to straddle said side at the notches 32 in these plates, as represented more particularly in Figs. 2 and 3.

Where the scaffold is to be of such length 50 that it is either impossible or impracticable to form the platform of single lengths of planking, it is necessary to break joints. By preference this would be done as shown in Figs. 2 and 3, namely, by overlapping 55 the adjacent ends of the planking where they extend over the cross-pieces 7, in which case, by preference, each plank adjacent the

frames 9, is provided with a plate 31, as hereinbefore explained.

It will be readily understood from the 60 foregoing that by constructing a scaffold in accordance with my invention, a safe and economical form of structure may be produced at relatively small cost.

It is oftentimes desirable that a roof be 65 provided for the scaffold to protect the workmen or materials supported on the platform. This I accomplish in a very simple and economical way by providing a series of uprights 34, one for each hoisting 70 frame. These supports are in the form of bars of metal applied flatwise to the outer faces of the outermost frame-sides 10, and held thereto by certain of the bolts 11 and shaft 18. The upper ends of the uprights 75 34 are connected together by bars 35, which form supports for planking 36, as represented, or, if desired, a canvas or tarpaulin covering may be supported from the framework thus provided.

While I have illustrated and described a particular construction embodying my invention, I do not wish to be understood as intending to limit it thereto, as the same may be variously modified and altered without 85 departing from the spirit of my invention.

What I claim as new, and desire to secure by Letters Patent, is:—

In a scaffold, in combination, a pair of cross bars having flanges at their upper 90 edges with portions cut away, hoisting frames at the ends of each cross bar and rigidly connected therewith at the cut away portions, each frame comprising a relatively long outside member and a short inside 95 member, a drum mounted between said members about which a supporting cable is adapted to be wound, pawl and ratchet mechanism associated with said drum for controlling its movement in one direction, 100 a second pair of cross members connecting said long outside members adapted to support a covering, and a floor positioned on said first pair of cross members, said floor having means associated with the boards 105 adjacent the hoisting frame adapted to contact therewith and prevent relative movement of the frames toward or from each other.

EDWARD J. GOLDEN.
